FLEXIBLE COVER FORMING MACHINE

Alfred Vischer, Jr., Park Ridge, Ill., assignor, by mesne assignments, of twelve-thirtieths to Alfred Vischer, Jr., two-thirtieths to William Vischer, two-thirtieths to Alfred Vischer, III, two-thirtieths to Alfred Vischer, Jr., as trustee, four-thirtieths to Walter W. Zitzewitz, four-thirtieths to Elmer K. Zitzewitz, one-thirtieth to Gertrude J. Zitzewitz, one-thirtieth to Barbara O. Zitzewitz, and two-thirtieths to Gertrude V. Bouton

Application August 1, 1945, Serial No. 608,105

6 Claims. (Cl. 153—54)

1

My invention relates generally to flexible cover forming machines, and more particularly to a machine for the quantity production of flexible covers of the type disclosed in my prior Patent No. 2,282,011.

In the manufacture of the covers of pressure cookers of the type shown in the aforesaid patent, some difficulty has been encountered in forming the covers to render them flexible and to introduce the stresses necessary to cause the cover to snap from its closed to open position, and vice versa. In the past, such stresses were introduced by securing the dished cover in the chuck of a lathe and applying the flexing force by means of rollers in the manner of a conventional spinning operation. While such forming of the covers by a spinning process was practical for covers of smaller diameters, it was inadequate for covers of larger size. Even though the lathe was equipped with special tools and fixtures for applying the pressure through the rollers, it was found that the application of the torque to the cover at its center tended to distort the shape of the cover, and was therefore not satisfactory, especially for covers of larger diameters.

It is therefore an object of the invention to provide an improved machine for substantially automatically flexing covers of the type shown in said patent, to introduce the necessary stresses and flexibility.

A further object is to provide an improved cover flexing machine in which the torque is applied to the cover near the peripheral edge thereof.

Other objects will appear from the following description, reference being had to the accompanying drawings, in which:

Fig. 1 is a plan view of the machine;

Fig. 2 is an end elevational view thereof;

Figs. 3 and 4 are transverse sectional views thereof, taken on the lines 3—3 and 4—4, respectively, of Fig. 1;

Figs. 5 and 6 are sectional views of the gear drive, taken on the lines 5—5 and 6—6, respectively, of Fig. 7;

Fig. 7 is a horizontal sectional view, taken on

2

the plane of the main drive shaft, and showing particularly the means for operating the pressure bails;

Fig. 8 is a horizontal sectional view showing the drive gearing;

Fig. 9 is a fragmentary sectional view showing the clutch tripping mechanism;

Fig. 10 is a fragmentary sectional view, taken on the line 10—10 of Fig. 1; and

10 Fig. 11 is a fragmentary sectional view, taken on the line 11—11 of Fig. 2.

In general, the purpose of the machine is to flex a dished circular cover 20 of the general shape shown in full lines in Fig. 3, to the shape shown 15 in dotted lines in said figure, such flexure taking place while the cover is rotating, and thus by cold working removing and imparting stresses to the cover which will render it flexible and cause it to snap from its warped to its relatively flat shape, and vice versa, upon release and application of the requisite forces at its center and at least two diametrically opposite points along its periphery.

The cover 20 is made of stainless steel, thus 25 having the necessary elasticity and strength to serve as a cover for pressure cookers, in which the aggregate force applied may be in the order of 2000 pounds.

The machine comprises a frame 22 preferably 30 of cast iron, having a bearing bracket 24 bolted thereto. The bracket 24 has a pair of bearings 26 for a shaft 28. A double V belt pulley 30 is adapted to be coupled to the shaft 28 by a suitable clutch mechanism contained within a housing 32. This clutch mechanism includes a stop lug 34 which, when arrested by the end of a control rod 36, declutches the pulley 30 from the shaft 28.

The clutch control rod 36 is slidably mounted 40 in a pair of bearings 38 which are suitably mounted on the bearing portions 26 of the bracket 24. The rod 36 has an operating knob 40 secured to one end and is normally urged to the right (Fig. 2), to cause its end to lie within the path of the stop 34, by a coil spring 42, compressed between

one of the bearing blocks 38 and a collar 44, the latter being suitably secured to the rod 36. The rod 36 also has a bushing 46 secured thereto, this bushing having a frusto conical latching portion 48 engageable in a notch 50 formed in a latch 52. The latch 52 is pivoted on a stud 54 and is biased to move counterclockwise (Fig. 2) by a tension spring 56.

The latch 52 has a sidewardly extending lug 58 adapted to be engaged by a clutch release arm 60 secured to the end of a shaft extension 62 on shaft 131.

As shown most clearly in Fig. 8, the shaft 28 has frictional drag applied thereto by a clamp 64 having a suitable liner 66 of leather or the like. The clamp 64 is held from rotation by a projection 68 thereof, which fits in a slot 70 formed in an anchor plate 72, the latter being suitably secured to the bearing bracket 26. The degree of friction applied by the clamp 64 may be adjusted by means of a bolt 74. By virtue of the friction applied to the shaft 28 by the clamp 64, a small load is continuously placed on the shaft 28 to assure proper operation of the clutch mechanism contained in the housing 32.

The shaft 28 has a drive pinion 76 (Fig. 8) pinned thereto, this pinion meshing with a spur gear 78 pinned to a counter-shaft 80. The shaft 80 is mounted in suitable bushed bearings 82, and has a bevel pinion 84 pinned to the end thereof. The bevel pinion 84 meshes with a pair of bevel gears 86, 87, the gear 87 being pinned to a shaft 88, while the hub of the bevel gear 86 interlocks with a sleeve 90 which is rotatably mounted on the shaft 88. The sleeve 90 forms part of a driving roller 91, having an annulus 92 of suitable friction material, such as fiber or compacted fabric, clamped thereto by a pair of rings 94, 95, the clamping being effected by hollow head cap screws 96 threaded in the clamping ring 95. The sleeve 90 is maintained in interlocking engagement with the bevel gear 86 by a collar 98 secured to the shaft 88.

As best shown in Fig. 7, a second driving roller 99 is provided by a sleeve member 100 pinned to the shaft 88 and having its frictionally driving annulus 102 clamped to the sleeve 100 by clamping rings 104, 105, the clamping pressure being applied by hollow head cap screws 106 threaded in the flange of the sleeve 100. From the foregoing, it will appear that the friction driving rollers 91 and 99 will be driven in opposite directions.

The cover 20 to be flexed has a central perforation which is engaged by a locating pin 108 (Fig. 3) guided for vertical movement in a bushing 110. The bushing 110 is secured in the upper end of a pedestal 112 forming part of the frame 22, and the locating pin 108 is held in its uppermost position by a compressed coil spring 114. The pedestal 112 also provides a central support for the main shaft 88, a suitable bearing bushing 116 being secured in the pedestal 112 by set screws 118. The upper end of the bushing 110 is chamfered to provide a bearing surface for the central portion of the cover 20.

The cover 20 is adapted to be clamped against the driving rollers 91, 99, by a pair of idler rollers 120, 121, (Figs. 1 and 3). These idler rollers are mounted for free rotation upon a shaft 122, the ends of the shaft being eccentric and suitably journaled in bearings 124, 125. A handle 126 is secured to the shaft 122 so that when it is swung from the position in which it is shown in Fig. 3 to the position in which it is shown in Fig. 1, the

idler rollers 120 and 121 will be moved close to the driving rollers 91, 99, so as to clamp the peripheral edge of the cover 20 between them, and thereby enable the driving rollers 91, 99 to rotate the cover 20.

A pair of bails 128, 129 are suitably journaled on pins 130 and shaft 131. The pins 130 are rigidly secured in the frame 22, while the shaft 131 (Fig. 9) is rotatable in the frame and is non-rotatably secured to the bail 129 by a plate 132 which has a splined connection with the end of shaft 131. The shaft 131 is formed integrally with its reduced diameter end portion 62 which carries the clutch release arm 60.

Each of the bails 128, 129 has a gear segment 134 formed integrally therewith at each end, these segmental gears being in mesh as shown in Fig. 6. The bails are rocked upon their pivots by a link 136 (Figs. 3 and 4), the link being pivoted to the bail 128 by an eccentric stud 138 which is locked in adjusted position by a set screw 140. The link 136 is held in position by a lug 141 secured to the bail 128. The other end of the link 136 has a large bore 142 (Fig. 7) to receive an eccentric 144, the link being held on the eccentric by a keeper plate 146. The eccentric 144 is formed integrally with a sleeve 148 which extends through a suitable bearing opening in the frame 22, and has a plate 150 splined thereto. An integral gear 152 is riveted to the plate 150. A similar internal gear 154 is secured to a fixed gear housing 156 and the latter is closed by a plate 158 which is secured to the frame 22.

A pinion 160 meshes with both of the internal gears 152 and 154, being mounted on an eccentric 162 which is pinned to the main shaft 88. Suitable anti-friction bearing assemblies 164 are provided for the pinion 160. As illustrative, the internal gear 152 may have sixty teeth, while the internal gear 154 has fifty-nine teeth, and the pinion 160 may have fifty-six teeth. Thus, as the pinion 160 rolls around the stationary internal gear 154, it will cause the internal gear 152 to rotate $\frac{1}{60}$ of a revolution for each revolution of the main shaft 88.

Each of the bails 128, 129 has a boss 166 near its center to receive a bearing stud 168. A forming roller, comprising a bearing bushing 170 and a fiber disc 172 clamped to the bushing 170 by side plates 174, is mounted for free rotation upon each of the studs 168.

In forming a cover, the dished disc is placed in the position indicated in full lines in Fig. 3, with the locating pin 108 extending but a short distance through the perforation at the center of the cover. Diametrically opposite portions near the edge of the cover rest upon the driving rollers 91, 99. The handle 126 is then swung to the position in which it is shown in Fig. 3, thereby, due to the eccentric mounting of the shaft 122, bringing the idler rollers 120, 121 into engagement with the cover and pressing the latter firmly against the driving rollers 91, 99. The machine is then started by pulling on the knob 40 (Fig. 2) to remove the end portion of the rod 36 from engagement with the lug 34, thereby permitting the clutch to operate and effect a driving connection between pulley 30 and the shaft 28. The rod 36 is latched in retracted position by the engagement of the conical portion 48 of the collar 46 in the notch 50 of latch 52. The main shaft 88 is thus driven through the pinion 76, spur gear 78, bevel pinion 84 (Fig. 8) and bevel gear 87. The driving roller 91 is driven in a direction opposite to that of the shaft 88.

through the bevel gear 86. The cover, clamped against the driving rollers 91, 99, is thus rotated, and as it rotates the eccentric 144 (Fig. 7) is rotated through the speed reducing gearing 152, 154, 160, at a speed $\frac{1}{60}$ of that of the shaft 88. The bails 128, 129 are thus slowly swung from the positions in which they are shown in full lines in Fig. 3, successively to the positions in which they are shown in dotted lines.

The cover is thereby flexed along successive diameters to the intermediate and fully warped shapes in which it is shown in dotted lines in Fig. 3, such flexure being accomplished by the engagement of the forming rollers 172 with the cover 20 at substantially diametrically opposite points near the edge thereof. The flexure of the cover is continued as the bails 128, 129 return to their normal positions, as shown in full lines in Fig. 3.

As the bails approach their normal positions, the arm 60 (secured to the end 62 of the shaft 131, Fig. 9) engages the sidewardly extending lug 58 (Fig. 2) of the latch 52, swinging the latter clockwise and permitting the spring 42 to move the end of the rod 36 into position for engagement with the lug 34, thereby tripping the clutch within the housing 32 and stopping the machine. After swinging the handle 126 clockwise approximately 180° from the position in which it is shown in Fig. 3, to disengage the idler rollers 120, 121, the cover may be removed from the machine, since now in its warped condition it easily clears the locating pin 108.

It has been found that covers flexed in this machine are uniformly worked to introduce stresses which give it the requisite properties to make it snap to its closed position when it is used, and to cause it to assume a normally warped shape. This makes it possible for the cover to be inserted in an inwardly flanged container having an opening of lesser diameter than that of the cover, as more fully disclosed in my aforesaid patent.

While I have shown and described a preferred embodiment of my invention, it will be apparent that numerous variations and modifications thereof may be made without departing from the underlying principles of the invention. I therefore desire, by the following claims, to include within the scope of the invention all such variations and modifications by which substantially the results of my invention may be obtained through the use of substantially the same or equivalent means.

I claim:

1. In a machine of the class described, the combination of a pair of spaced driving rollers, means to press a disc against said rollers to secure frictional engagement therewith and thus to cause rotation of the disc, a drive shaft, a train of gearing connecting said drive shaft to said rollers to cause the latter to rotate in opposite directions, a pulley mounted on said drive shaft, a disengageable clutch connecting said pulley to the drive shaft, a manual control element, means for latching said element in a position to cause engagement of the clutch, a pair of forming rollers engageable with the upper surface of the disc at points near the periphery thereof and intermediate the points at which the driving roller engages the disc, means driven through said gearing for swinging said forming rollers downwardly and inwardly with respect to the center of the disc thereby to bend the disc into inverted trough shape successively along angularly incremental

5 diameters as the disc is rotated and thereafter to swing the forming rollers upwardly and outwardly, and a latch releasing member operated by said last named means when the forming rollers have passed through a complete oscillatory cycle, thereby to release said manual control element and cause disengagement of said clutch.

2. In a machine of the class described, a central vertically extending locating pin, a horizontal shaft beneath said locating pin, a driving roller fixed to said shaft, a second driving roller rotatable on said shaft, means for driving said rollers in opposite directions, a pair of bails mounted for pivotal movement and interconnected so as to swing in opposite directions, an eccentric for swinging said bails, a speed reducing gearing connecting said eccentric and said shaft, a roller mounted for free rotation on each of said bails, a pair of idler rollers for pressing a disc to be warped against said driving rollers, and means for moving said idler rollers toward said driving rollers to cause the idler rollers to press the disc against the driving rollers.

3. The combination set forth in claim 2, in which said speed reducing gearing for driving said eccentric comprises a fixed internal gear, a rotatable internal gear connected to the eccentric, said internal gears being of the same size but having different numbers of teeth, a pinion meshing with both of said internal gears, and an eccentric connected to said shaft and forming a bearing for said pinion whereby said pinion will roll around said internal gears and cause the movable internal gear to rotate through a small angle upon each revolution of the shaft.

4. In a machine of the class described, the combination of a pair of driving rollers, means for rotating said rollers at the same speed in opposite directions, idler rollers movable toward and away from said driving rollers for maintaining a cover to be formed in frictional contact with said driving rollers at diametrically opposite points of the cover, a pair of forming rollers engageable with a cover rotated by said driving rollers at substantially diametrically opposite points near the periphery of the cover and spaced intermediate the points at which the cover is engaged by the driving rollers, and means for swinging said forming rollers inwardly and downwardly with respect to the center of the cover, thereby to warp the cover into a generally trough-like shape along successive angularly incremental diameters as the cover is rotated by the driving rollers.

5. In a machine for warping flexible generally circular covers, the combination of means for gripping the cover at two diametrically opposite spaced points and rotating the cover about a central polar axis, a pair of elements engageable with the cover at substantially diametrically opposite points intermediate the points at which the cover is engaged by the gripping and rotating means, and means for swinging said elements downwardly and inwardly thereby to warp the cover into a generally inverted trough-like shape as it is rotated by the driving means.

6. In a machine for cold working generally circular flexible covers, the combination of means for frictionally engaging the cover at diametrically opposite points adjacent the edges thereof, said means being driven to rotate the cover about its center, a pair of elements engageable with said cover at points spaced substantially 90° from the points at which said frictional means engage the cover, and means for slowly moving said ele-

ments downwardly and inwardly thereby to flex said cover successfully about angularly incremental diameters as the cover rotates.
